Sweden, a corporation of Sweden

Application February 23, 1940, Serial No. 320,298
In Sweden February 13, 1939

10 Claims. (Cl. 185—40)

The invention relates to a spring starting device for internal combustion motors provided with springs which are in strained condition adapted to deliver a turning moment to the crank shaft of the motor. The invention is primarily intended for motors operating with crude oil, for instance for two-stroke cycle Diesel-engines. The invention has for its main object to provide a starting device of this kind which is utterly reliable in operation and simple to handle. A turning moment is by the springs applied to the crank shaft of a Diesel-motor, for example, being great enough to overcome the frictional resistance within the motor even at low temperatures, and simultaneously also great enough to supply the work required to obtain a quick and powerful compression stroke with a rapid rise of the temperature during the compression stroke in consequence thereto, without too much of the heat formed through the compression being transmitted through convection to the cylinder walls or the surface of the piston. The energy supplied by the springs may during half a revolution of the motor exceed and be the double of or still greater than the intrinsic power development of the combustion motor during one working stroke, without this causing any difficulty or too large dimensions in the apparatus. The motor, the piston of which at the moment of starting takes a position at the beginning of the compression stroke, compresses during this first compression stroke the stationary fresh air enclosed within the cylinder at a considerable speed. By reason of this the compression is rendered adiabatic as far as possible, partly by the fact that it takes place without disturbing eddies apt to increase the heat transmission to the walls of the compression chamber, and partly by the fact that this first compression takes place rapidly, whereby the time for heat transmission is reduced to a minimum. As a consequence, a powerful and safe ignition of the fuel is produced, ensuring a safe, quick and immediate start.

In addition to the advantage of the rapid and safe start, the motor unit according to the invention may in its entirety be made appreciably lighter, inasmuch as a fly-wheel of considerably smaller weight may be used. In a two-stroke cycle motor, for example, the fly-wheel may thus be advantageously arranged within the crank-casing and simply be concentrated to the cranks, whereby the detrimental space is also reduced in the crank casing, while the total shaft length of the motor becomes smaller.

Other and more detailed objects of the invention together with the advantages to be derived from its use will be more fully explained in the following description of the several forms of apparatus for carrying the invention into effect,

which are illustrated in the accompanying drawings forming part of this specification.

Fig. 1 illustrates more or less diagrammatically a starting device according to the invention in a perspective view;

Fig. 2 shows a projection of a detail of Fig. 1 on a somewhat enlarged scale;

Fig. 3 shows a section on the line III—III of Fig. 4 through a spring starting device in accordance with the invention;

Fig. 4 is a section on the line IV—IV of Fig. 3. In Figs. 3 and 4, as well as in the subsequent Figures, certain parts are removed for sake of clearness;

Fig. 5 is a plan view of a detail pertaining to the same embodiment;

Fig. 6 shows a section on the lines VI—VI of Figs. 4 and 7, illustrating the springs together with a crank mechanism intended for straining the same;

Fig. 7 is a section on the line VII—VII of Fig. 6;

Fig. 8 is a plan view of a detail of Fig. 6;

Fig. 9 is a section on the lines IX—IX of Figs. 4, 7, and 10;

Fig. 10 is a section on the line X—X of Fig. 9.

In the embodiment according to Figs. 1 and 2, reference numeral 50 denotes a shaft which is rotatably mounted in bearings 31 and is formed with cranks 51 connected to two powerful helical springs 52, for instance by rods 53, 54. The springs 52 are opposed but being connected to cranks set 180° apart, augment each other. When the shaft 50 is rotated by the motor or by hand, they are strained and released at the same time. The shaft 50 carries two friction disks 55 fixed thereto which are adapted to cooperate each with friction clutches 56. These friction clutches embrace the disks 55 and are open in one place where they are provided with projecting portions 56a, 56b. A bell crank lever 57 is pivotally mounted on the portion 56a as at 58. One end of the lever 57 is pivotally connected to a link or the like 60, as at 59, which is mounted at its other end on the portion 56b as at 70. Each lever 57 is pivotally connected at its other end to a sort of connecting rod 72, as at 71, which is in turn pivotally mounted on a crank 73 on a shaft 74, which is rotatably supported in fixed bearings 75. When the shaft 74 is turned in the direction indicated by the arrow 76, the crank 73 being in the position shown, the right hand rod 72 is placed under tension and pivots the right hand lever 57 in a counter-clockwise direction, as viewed in Fig. 2, about the point 58 to thereby cause the

link 60 to draw the clutch parts 56a and 56b together so as to tightly clamp them around the disk 55. Thereafter, continued rotation of right-hand crank 73 cannot cause further pivoting of arm 57 about point 58 and hence the both parts 56a and 56b of the clutch are caused to rotate

and transmit rotation to disk 55 in the direction of arrow 71. In the meantime the left-hand rod 72 is placed under compression by the rotation of crank 73 and pivots the left-hand lever 57 in a clockwise direction about point 58, thus spreading the parts 56a and 56b of the left-hand clutch. This clutch is thereby maintained in disengagement from disk 55, and continued rotation of crank 73 causes the left-hand clutch 56 to rotate freely with respect to the disk 55 in the opposite direction thereto. The right-hand clutch 56 remains engaged to the disk 55, as above described, during a one half revolution of shaft 74. Thereafter, this clutch becomes disengaged, and inasmuch as the cranks 73 are set 180° apart, the left-hand clutch becomes engaged and continues the rotation of the shaft 50 in the direction of arrow 77. The disks 55 and the shaft 50, respectively, move comparatively slowly during the straining of the springs, so that any lubricating oil present between the friction surfaces of the members 55, 56 will have sufficient time for being pressed off these surfaces each time the members are to effect another frictional engagement.

Rigidly secured to the shaft 74 is a ratchet disk 83 and an operating lever 84 which may be movably arranged between guide rails 85 in known manner. The lever 84 is provided with a pawl 86 engaging the ratchet teeth of the disk 83. Extending from the lower portion of the lever 84 in Fig. 1 is an arm 87 which is pivotally connected to an arm 88. The arm 88 is connected with a spring 89 tending to move the same against a disk 90 on the shaft 50, said disk being provided with a notch 91.

By reciprocating the operating lever 84 the shaft 74 will be moved round step by step. The lever devices extending from the two cranks 73 are caused alternately to strain and to release the respective friction members 56 for every half a revolution, and the shaft 50 is thus turned while the springs 52 are being strained. This straining of the springs takes place during a turning movement of the shaft 50 of half a revolution. When the springs 52 have been brought into their strained position they are on dead center, and the arm 88 will snap into the notch 91 under the influence of the spring 89. A further reciprocation of the lever 84, and hence of the lever 87 which is fixed thereto, causes the arm 88, the lower end of which is in engagement with notch 91, to rotate the shaft 50 sufficiently to turn the cranks 51 off dead center, whereupon the stressed springs 52 apply a large torque to the shaft. While turning of the shaft 50 by means of the lever 87 and arm 88, does not result in the high torque multiplication which is obtained by the mechanism including the clutches 56, it nevertheless is sufficient to turn the cranks 51 off dead center, inasmuch as this does not require any additional stressing of the springs 52, but the force need be only sufficient to overcome friction.

The shaft 50 has a disk 92 rigidly secured thereon. Arranged about the disk 92 is a circular gripping member 93 which is in turn inserted into a drum 94 rigidly connected to the fly-wheel 21 and the crank shaft of the motor. When the spring-starter is not functioning, there is an annular clearance between the members 93 and 94. The elements 92, 93 are interconnected by a double-armed lever 95 and two links 96, 97. The gripping disk 93 is open in one place, and the links 96, 97 are pivotally connected each with an open end of the gripping disk. The link 96 is pivoted to the lever 95 at 98, and the link 97 at 99.

The lever between the points 98 and 100, which latter point designates the bearing point between the lever arm 95 and the disk 92, is preferably longer than the lever between the points 98 and 99. When, upon the realease of the spring force, the shaft 50 is quickly turned in the direction of the arrow 77, the gripping member 93 will immediately open under the influence of the lever-and link-device just described, and will be expanded against the drum 94 with a force of such magnitude that the drum and the motor shaft and fly-wheel connected thereto are clutched to the shaft 50 and hence rotated thereby. At the same time the gripping member serves as a little fly-wheel, the mass of which counteracts a sudden acceleration in the direction of rotation, whereby the member will have an increased tendency toward expanding radially at a beginning acceleration, and will thus instantaneously be firmly pressed against the drum 94 when the springs 52 pass through the dead point position.

The shaft 74 carries a rigid ratchet wheel 101 cooperating with a pawl 102 on an arm 103 which is pivotally connected to the shaft 74. The opposite end of the arm 103 is formed with a contact shoe 104. A part rigidly connected with the motor shaft, such as the drum 94, is formed with an eccentric surface 105. An arm 106 is pivotally mounted in a rigid support 107, and is pivotally connected with its other end to an arm 108. The arm 108 is provided with an end portion 109 which is preferably bifurcated and adapted to embrace the arm 103. A spring 111 is adapted to actuate the arm 108, so that the latter tends to move in a direction toward the arm 103. A spring 110 is connected with its ends to the arms 103 and 108 and tends to approach these arms to each other. The shaft 50 carries a disk 112 provided with a notch 113, and the arm 106 is provided with a boss 114 corresponding thereto.

When the spring members 52 have been brought into their strained position of rest, the lower end of the arm 88 in Fig. 1 is in engagement with the locking notch 91. At the same time the tooth 114 of the arm 106 is in engagement with the notch 113 in the disk 112. The latter has resulted in that the arm 108 has been moved by the springs 110, 111 against the arm 103, the fork 109 having raised the arm 103 and its shoe 104 out of contact with the eccentric surface 105.

By turning the operating lever 84 in the direction of the arrow 76, the arm 88 actuates the disk 90 and the shaft 50 so that the springs 52 snap over from their strained position of rest and are brought into function. At the release of the spring force the gripping disk 93 immediately strikes out against the drum 94 and provides a rigid connection between the shaft 50 and the drum, whereby the movable masses of the motor are accelerated and the motor is started. After the spring work has been delivered to the motor upon half a revolution, the pressing force exerted on the drum 94 through the lever device 95, 96, 97 ceases, the drum 94 then continuing to rotate alone together with the crank shaft of the motor. The release of the spring force resulted in that the end portion of the arm 88 and the boss 114 of the arm 106 were turned outwardly so as to bear on the circular external surface of the disks 90 and 112, respectively. The arm 108 has thus been moved away from the arm 103, the spring 110 pulling the same with the contact shoe 104 down onto the surface 105. Upon continued rotation of the motor an oscil-

latory reciprocating movement is imparted to the arm 103 by reason of the eccentric surface 105, the pawl 102 then turning the disk 101 and the shaft 74 in a stepwise fashion in the direction of the arrow 76. The shaft 50 is thus rotated by the motor so as to stress the springs 52. When the strained position of rest of the springs has again been reached, the pawl 88 and the boss 114 will again enter their respective notches. The arm 103 is pulled against the arm 106 so as to 10 raise the contact shoe 104 so that the rotation of shaft 74 is automatically interrupted. The springs 52 are hence in fully stressed condition, and are ready to start the motor the next time.

As will appear from the above, the starting device may be charged either manually or automatically by the motor itself. By the fact that the starting mechanism has a very small mass relatively to the movable parts of the motor, the same may be released or connected to and disconnected from the motor without disadvantage even at the full number of revolutions. Therefore, if the starting device would happen to be released by mistake while the motor is in operation, this will cause no damage whatever to the apparatus. It may thus be attended to by technically quite unskilled people.

In the embodiment according to Figs. 3-10, which shows a constructive realization of the inventive idea disclosed in Figs. 1 and 2, the same reference numerals have been used as in these figures for corresponding parts. The starting device is arranged in a rigid outer casing 120, in which the shafts 50 and 74 are mounted. As described hereinabove, the shaft 50 is formed with cranks 51 cooperating with connecting rods 53, 54, for instance in the form of U-bent round irons or the like. The connecting rods 53, 54 are pivotally mounted as at 121 (Fig. 6) in an upper and a lower yoke 122 and 123, respectively. These yokes extend between parallel guides 124 (see particularly Fig. 8). The guides 124 are rigidly connected with the side walls of the external casing by means of screws or the like. The guides 124 are each surrounded by a helical spring 52, the end portions of these springs bearing against the yokes 122, 123. At the straining of the starting device the end portions of the springs are pressed toward one another, so that the yokes 122, 123 receive the same straining pressure.

The shaft 50 is formed with two cylindrical friction surfaces 55 (Fig. 4), preferably one on each side of the cranks 51, which surfaces are embraced by friction clutch members 56 of the same general construction as that described above in connection with Figs. 1 and 2. Thus the element 56a (Fig. 9) of the friction clutch is pivotally connected to the arm 57 as at 58, said arm being pivotally connected to the arm 72 as at 71, which latter arm is mounted on the respective cranks 73 (Fig. 4). The lever 57 is mounted as at 59 in the one end of the link 60, the other end of which is mounted in the clutch member 56b as at 60. As will be seen from Fig. 9, the pivot pin 59 is adapted to move freely relatively to the member 56a. When the shaft 74 is turned in the direction of the arrow 76, the two clutch members 56 are alternately brought into function so as to carry along the shaft 50 in the direction of rotation 77.

A handle 84 (see particularly Fig. 3) extends outside the casing 120. The handle 84 is connected over a coupling 125 to the shaft 74 in such manner that this shaft may be turned in the direction of the arrow 76 (Fig. 9) while be-

ing locked in the opposite direction. Pivotally secured to a coupling sleeve 126 carrying the handle is an arm 88 actuated by the spring 89, the other end of which arm is adapted to cooperate with a cylindrical portion of the shaft, which has a notch 91, as described above. The same cylindrical portion of the shaft 50 is provided with a notch 113 intended to cooperate with a boss 114 on the arm 106 mounted with its one end in the casing as at 107.

The drum 94 rigidly connected with the motor shaft surrounds the circular gripping member 93 which is movably connected to the shaft 50 over the links 95, 96, 97. When the starting device is not in function, there is a clearance between the member 93 and the drum 94. Provided in the drum 94 is the eccentric surface 105. Over a second coupling 125 the shaft 74 carries the arm 103 provided with the contact shoe 104. Through the rod 108 the arm 103 is in movable cooperation with the arm 106, which, when the boss 114 thereof is adjacent the recess 113 brings the contact shoe 104 out of engagement with the eccentric surface 105 under the influence of the spring 110. The spring 110 is preferably arranged within a sleeve 130, which is pivotally mounted at its upper end on the arm 103, as shown in Fig. 3.

The mode of operation of the apparatus according to Figs. 3-10 is altogether the same as that described hereinabove.

The invention may obviously be varied in many respects without departing from the idea of the same. It is applicable in all types of internal combustion motors. The primary shaft 50 may be provided with gear wheels, the secondary crank shaft being at the same time replaced by a shaft provided with a pinion meshing with said gear wheel. When the secondary shaft is then caused to rotate by means of the members 83 and 101 or 125 the shaft 50 obviously obtains a slower rotary movement corresponding to the ratio of gear. On discharging the spring to start the clutches operate on the secondary shaft 74 alone in the same manner as the clutch 55, 56 operate on the shaft 50, as described above.

What I claim is:

1. A starting device for internal combustion motors including a starter shaft, spring means having one end connected to a stationary abutment and the other end connected to said shaft eccentrically with respect to the axis of rotation of said shaft so as to be stressed by a one-half revolution of said shaft and to be relieved of stress by the following one-half revolution of the shaft in the same direction, and means for connecting said starter shaft to the crank shaft of the motor at a one to one speed ratio.

2. A starting device for internal combustion motors including a starter shaft, spring means connected to said shaft eccentrically with respect to the axis of rotation of said shaft so as to be stressed by a one-half revolution of said shaft and to drive the shaft during the subsequent one-half revolution in the same direction, and means including a clutch for connecting said shaft to the motor shaft at one to one speed ratio, said clutch being automatically engageable by a sudden acceleration of said starter shaft and automatically disengageable by rotation of the motor shaft at a speed higher than that of said starter shaft, and remaining disengaged during relatively slow rotation of said starter shaft.

3. A starting device for internal combustion motors including a starter shaft, spring means connected to said shaft eccentrically with respect to the axis of rotation of said shaft so as to be stressed by a one-half revolution of said shaft and to drive the shaft during the subsequent one-half revolution in the same direction, a drum secured to the shaft of the motor, a friction member associated with said drum, an arm eccentrically connected to said starter shaft and linked to said friction member so that relative rotation between said starter shaft and said member caused by sudden acceleration of the starter shaft and the inertia of the friction member causes said arm to frictionally engage said member with said drum.

4. A starting device for internal combustion motors including a starter shaft, spring means connected to said shaft eccentrically with respect to the axis of rotation of said shaft so as to be stressed by a one-half revolution of said shaft and to drive the shaft during the subsequent one-half revolution in the same direction, a drum secured to the shaft of the motor, a split band associated with said drum, an arm having one end eccentrically connected to said starter shaft, a first link connecting the other end of said arm to one end of said band, and a second link connecting an intermediate point of said arm to the opposite end of said band.

5. A starting device for internal combustion motors including a starter shaft, spring means connected to said shaft eccentrically with respect to the axis of rotation of said shaft so as to be stressed by a one-half revolution of said shaft and to drive the shaft during the subsequent one-half revolution in the same direction, clutch means for connecting said shaft to the motor shaft automatically engageable by a sudden acceleration of said starter shaft and automatically disengageable by rotation of the motor shaft at a speed higher than that of said starter shaft, and means for rotating said starter shaft to stress said spring at a speed so slow that said clutch means remains disengaged even if the motor shaft is stationary.

6. A starting device for internal combustion motors including a starter shaft, spring means connected to said shaft eccentrically with respect to the axis of rotation of said shaft so as to be stressed by a one-half revolution of said shaft and to drive the shaft during the subsequent one-half revolution in the same direction, clutch means for connecting said shaft to the motor shaft automatically engageable by a sudden acceleration of said starter shaft and automatically disengageable by rotation of the motor shaft at a speed higher than that of said starter shaft, a third shaft, means for rotating said third shaft step by step, one way clutch means for transmitting said rotary motion to said starter shaft to stress said spring, the speed of rotation of said starter shaft being so slow that the first mentioned clutch remains disengaged even if the motor shaft is stationary.

7. A starting device for internal combustion motors including a starter shaft, spring means connected to said shaft eccentrically with respect to the axis of rotation of said shaft so as to be stressed by a one-half revolution of said shaft and to drive the shaft during the subsequent one-half revolution in the same direction, clutch means for connecting said shaft to the motor shaft automatically engageable by a sudden acceleration of said starter shaft and auto-

5 matically disengageable by rotation of the motor shaft at a speed higher than that of said starter shaft, a third shaft, a lever ratcheted to said third shaft for slowly rotating it manually step by step, and one way clutch means for transmitting said rotary motion to said starter shaft to stress said spring, the speed of rotation of said starter shaft being so slow that the first mentioned clutch remains disengaged even if the motor shaft is stationary.

10 8. A starting device for internal combustion motors including a starter shaft, spring means connected to said shaft eccentrically with respect to the axis of rotation of said shaft so as to be stressed by a one-half revolution of said shaft and to drive the shaft during the subsequent one-half revolution in the same direction, clutch means for connecting said shaft to the motor shaft automatically engageable by a sudden acceleration of said starter shaft and automatically disengageable by rotation of the motor shaft at a speed higher than that of said starter shaft, a third shaft, a lever ratcheted to said third shaft for rotating it step by step, a cam rotatable by said motor shaft and operative to rock said lever, and one way clutch means for transmitting said rotary motion to said starter shaft to stress said spring.

20 9. A starting device for internal combustion motors including a starter shaft, spring means connected to said shaft eccentrically with respect to the axis of rotation of said shaft so as to be stressed by a one-half revolution of said shaft and to drive the shaft during the subsequent one-half revolution in the same direction, clutch means connecting said shaft to the motor shaft automatically engageable by a sudden acceleration of said starter shaft and automatically disengageable by rotation of the motor shaft at a speed higher than that of said starter shaft, a third shaft, a lever ratcheted to said third shaft for rotating it step by step, a cam rotatable by said motor shaft and operative to rock said lever, one way clutch means for transmitting said rotary motion to said starter shaft to stress said spring, and means for automatically disengaging said lever from said cam just before said starter shaft is rotated to a dead center position with respect to the eccentric connection with said spring.

30 40 50 10. A starting device for internal combustion motors including a starter shaft, spring means connected to said shaft eccentrically with respect to the axis of rotation of said shaft so as to be stressed by a one-half revolution of said shaft and to drive the shaft during the subsequent one-half revolution in the same direction, clutch means for connecting said shaft to the motor shaft automatically engageable by a sudden acceleration of said starter shaft and automatically disengageable by rotation of the motor shaft at a speed higher than that of said starter shaft, a third shaft, a lever ratcheted to said third shaft for rotating it step by step, a cam rotatable by said motor shaft and operative to rock said lever, one way clutch means for transmitting said rotary motion to said starter shaft to stress said spring, means for automatically disengaging said lever from said cam just before said starter shaft is rotated to a dead center position with respect to the eccentric connection with said spring, and a manually operable lever ratcheted to said third shaft for rotating said starter shaft past dead center.
